UNITED STATES PATENT OFFICE.

MIKAEL PEDERSEN, OF DURSLEY, ENGLAND.

CYCLE.

SPECIFICATION forming part of Letters Patent No. 634,585, dated October 10, 1899.

Application filed December 28, 1897. Serial No. 664,050. (No model.)

To all whom it may concern:

Be it known that I, MIKAEL PEDERSEN, a subject of the King of Denmark, residing at Dursley, England, have invented new and 5 useful Improvements in or Connected with Bicycles, (for which I have obtained a patent in Great Britain, No. 16,899, dated July 30, 1896,) of which the following is a specification.

My invention relates to bicycles having 10 frames constructed in the manner described in the specification of my former patent, No. 577,170, dated February 16, 1897, the object of my present invention being to provide improved means for jointing or connecting the 15 various parts of the frame, and it comprises the improvements hereinafter described.

In the accompanying drawings, Figure 1 is a perspective view of my improved frame. Fig. 2 is a side elevation of the head of the 20 steering-fork, drawn to a larger scale than Fig. 1, and Fig. 3 is a section on the line 3 3, Fig. 2, drawn to a still larger scale. Fig. 4 is a side elevation of the lower end of one side of the steering-fork, and Figs. 5 and 6 are 25 sections on the lines 5 5 and 6 6, respectively, of Fig. 4, drawn to a larger scale than said figure. Fig. 7 is a side elevation of the upper part of the frame in which the steering-fork is pivoted, and Fig. 8 is a rear elevation 30 of the same. Fig. 9 is a view of the connecting-piece of this part detached, and Fig. 10 is a section on the line 10 10, Fig. 8, drawn to an enlarged scale. Fig. 11 is a side elevation 35 of the rear part of one side of the frame at the fork end, and Figs. 12 and 13 are sections on the lines 12 12 and 13 13, respectively, of Fig. 11 looking in the direction of the arrow and drawn to an enlarged scale. Fig. 14 is an 40 underside view of the parts shown in Fig. 11. a a a are the tubes of the head of the front fork. These tubes are fitted into and 45 brazed or sweated in four holes formed in a plate b, as shown in Fig. 3. Over this plate is placed a conical cap c, having at its upper end the pivot-pin d, which works in a socket in the front of the frame. The lower part of 50 this cap is formed with four flaps or extensions e e, Fig. 2, which are also brazed or sweated onto the tubes. The lower ends of each pair of tubes a a of the front fork are 55 connected in the following manner—that is to say, each tube is flattened diagonally at its

end in such a manner that the rounding of the tube gradually diminishes toward the lower end, as shown in Fig. 4. The flattened portions 55 f of one tube are then placed between the flattened portions f' of the other tube, as shown in Figs. 5 and 6, the area of contact between the flattened portions of the two tubes being much greater at the bottom, Fig. 5, than at 60 the top, Fig. 6. These flattened portions, which at their lower end have an eye g for carrying the front-wheel axle, are brazed or sweated together.

I sometimes insert a piece of flat steel be- 65 tween the flattened portions of the tubes in order to act as a stiffener.

The jointing of the pair of tubes h h and the pair of tubes i i is effected by uniting them to a steel forging, Fig. 9, having two 70 arms or limbs j k, to the former of which the tubes h h are attached and to the latter of which the tubes i i are attached, the said forging having the socket k', adapted to fit onto the pivot-pin d of the fork and having the 75 eye l for the seat connection. The tubes of each pair are flattened on the sides which come into contact with the limbs j k of the said forging in a manner which will be clearly understood by reference to Fig. 10, the said flattened surfaces being inclined relatively with 80 the axes of the tubes, as clearly shown in Fig. 8.

The tubes h h, hereinbefore referred to, are at their lower ends connected to the fork ends 85 m for carrying the rear axle. Each fork end m has upon it two tongues n n—namely, one for one of the tubes h and another for one of the bottom tubes o—and each tube h and o is split at the end to embrace its tongue n on 90 both sides, the portion of the tube on each side of the tongue being gradually flattened out, so that the rounding of the tube merges into the flat surfaces or flanges p p, which flat surfaces or flanges are brazed or sweated to 95 the sides of the tongue, as clearly shown in Figs. 12, 13, and 14.

The bottom bracket q, to which the several pairs of tubes i i, o o, r r, and s s of the frame are connected, is constructed with sockets for 100 the tubes in the usual manner or with tongues similar to the tongues n n on the fork ends, each of the said tubes being split and brazed on its tongue. The front ends of the tubes

r r, which are in connection with the steering-fork, are connected to a tongue on a swivel-piece *t* in the same manner that the tubes *h h* and *i i* are connected to their tongues *j k*. The upper ends of the tubes *s s* are also connected together by a tongue in a similar manner to the tubes *h h* and *i i*.

Having now particularly described and ascertained the nature of my said invention and in what manner the same is to be performed, I declare that what I claim is—

1. A bicycle-frame comprising among its members, a front fork, consisting of a plurality of bars, provided at their lower ends with means for engaging the axle of the front wheel, and converging at their upper ends, a plate provided with apertures to receive and retain the ends of said bars, and a conical cap inclosing said plate and the ends of said bars and provided with a pivot-pin, substantially as described.

2. A bicycle-frame comprising among its members the front fork, consisting of four bars, united in pairs at their lower ends to engage the axle of the front wheel, one bar of each pair having flattened portions overlapping flattened portions of the other and brazed thereto, the upper ends of said bars converging, a plate provided with apertures to receive and hold the ends of said bars, and a conical

cap inclosing said plate and the upper ends of said bars and secured thereto, and provided with a pivot-pin, substantially as described.

3. A bicycle-frame comprising among its members the front fork, consisting of four bars united in pairs at their lower ends to engage the axle of the front wheel, one bar of each pair having flattened portions overlapping flattened portions of the other and brazed thereto, the upper ends of said bars converging, a plate provided with apertures to receive and hold the ends of said bars, and a conical cap inclosing said plate and the upper ends of said bars, said cap being provided at its upper end with a pivot-pin and at its lower end with a series of extensions or arms, one of which engages and is secured to each of said bars, substantially as described.

4. A bicycle-frame comprising among its members, two pairs of converging bars, the adjacent faces of each pair being flattened at an angle to their axes, and a forging provided with an eye, and a pair of flattened arms each arm lying between and secured to the flattened portions of one of said pairs of bars, substantially as described.

MIKAEL PEDERSEN.
